UNITED STATES PATENT OFFICE

127,163

DESIGN FOR AN AIRPLANE

Aristede A. Theodoropoulos, New Haven, Conn.

Application May 8, 1940, Serial No. 92,214

Term of patent 7 years

To all whom it may concern:

Be it known that I, Aristede A. Theodoropoulos, a citizen of the United States, residing in New Haven, in the county of New Haven and State of Connecticut, have invented a new, original, and ornamental Design for Airplanes, of which the following is a specification, reference being had to the accompanying drawings, forming part thereof, in which

Fig. 1 is a top plan view of an airplane showing my new design;

Fig. 2 is a front elevational view of the same; Fig. 3 is an enlarged side elevational view of the airplane;

Fig. 4 is a bottom plan view thereof; and Fig. 5 is an enlarged sectional view on line 5—5 of Fig. 1.

I claim:

The ornamental design for an airplane, substantially as shown.

ARISTEDE A. THEODOROPULOS.
